ELLIS W. COOPER, OF BLOOMFIELD, NEW JERSEY, ASSIGNOR TO R. HOE AND CO., OF NEW YORK, N. Y., A CORPORATION OF NEW YORK.

INKING MECHANISM.

1,173,488.

Specification of Letters Patent. Patented Feb. 29, 1916.

Application filed June 14, 1913. Serial No. 773,686.

To all whom it may concern:

Be it known that I, ELLIS W. COOPER, a citizen of the United States, residing at Bloomfield, county of Essex, and State of New Jersey, have invented certain new and useful Improvements in Inking Mechanism, fully described and represented in the following specification and the accompanying drawings, forming a part of the same.

10 This invention relates to certain improvements in inking mechanism for printing machines.

The invention has for its object to provide a construction of simple and improved design whereby a pre-determined quantity of ink may be taken from a suitable ink supply and delivered to the form member of a printing couple at each printing operation of the couple, the measured quantity of ink 20 being delivered or fed under pressure, thus insuring an even and constant supply of ink to the printing member of the couple at each operation thereof.

Other objects of the invention will appear 25 in the description of a mechanism embodying the same, which will now be given in connection with the accompanying drawings, in which:

Figure 1 is a plan view, partly in section, 30 of so much of a printing machine embodying the invention as is necessary for an understanding thereof; Fig. 2 is a side elevation, partly in section, of the construction shown in Fig. 1; Fig. 3 is a section on line 35 3—3 of Fig. 2, showing the ink measuring and feeding means, and Fig. 4 is a side view, partly in section, of a modified form of mechanism which may be employed.

Referring now to the drawings, the machine 40 chosen to illustrate the invention is a rotary machine, though it will be understood that the invention is adapted for use in machines other than rotary. One printing couple of such a machine is shown comprising form cylinder 1 and impression cylinder 2. Coöperating with the form cylinder are the usual form rollers 3, 4, which take ink from a distributing cylinder 5. In accordance with the invention as 45 hereinafter referred to, the cylinders and rollers all operate at the same surface speed.

Machines embodying the invention will 50 include means for measuring out and delivering a predetermined amount of ink to the form member at each printing operation

thereof, the ink delivered being measured from a suitable source of supply and fed under pressure, whereby a constant and even distribution of ink is effected. The means employed for effecting this may be varied. In the construction illustrated, these means include a pair of gears 7, 8 carried on short shafts 9, 10, the gears being mounted in a casing 11 suitably secured in the frame of the machine. Ink is supplied to this casing by a pipe 12 from a suitable source of ink supply (not shown). These gears are operated intermittently to deliver at each printing operation of the form cylinder a predetermined amount of ink, this amount being determined by the distance the gears are caused to move at each operation. The means for effecting movement of the gears may be somewhat varied. They will, however, preferably be driven from one of the moving parts of the machine before referred to, and in the particular construction illustrated are driven from the distributing cylinder 5, which, as before stated, runs at the same surface speed as the form cylinder 1. For effecting the delivering movement of the gears from the distributing cylinder, shaft 14 of the distributing cylinder 5 is provided at one end with a cam 15 having a cam groove 16 in which takes a stud 17 fast on a yoke 18 on the shaft 14. Connected at one end to the yoke 18 is a rod 19 which at its other end is connected to one arm 20 of a bell crank lever pivoted on the short shaft 9 before referred to. The other arm 21 of this lever carries a pawl 22 on a pawl stud 26 which pawl cooperates with a ratchet 23 fast on the shaft 9. Through these connections, the gear 7 mounted on shaft 9 is given an intermittent rotary motion and with gear 8 acts to measure out from the ink supply a predetermined quantity of ink, depending on the throw of the pawl. The gears 7, 8, furthermore, form in effect a gear pump which causes the ink to be delivered from the casing under constant pressure. This construction is a convenient one, though it is understood that other means might be employed for effecting delivery of the ink under pressure.

Means for varying the quantity of ink delivered at each printing operation of the form cylinder are provided by the present invention, and these means are preferably 110

of such character that the quantity of ink may be varied, while the machine is in operation. In the particular construction illustrated this result is effected by adjusting the throw of the pawl. In the construction illustrated these means include an arm 24 pivoted on the short shaft 9, on one end of which arm is a guard plate 25 located below the pawl and on which the pawl is adapted to ride and be held out of engagement with the teeth of ratchet 23. The other end of this arm is formed into a curved plate 28, through the slotted portion of which there projects a stud 27 suitably secured to the casing 11, so that this slotted arm may be secured in any desired position by the clamp 29, thus throwing the guard to the right or left, and causing the pawl to come into operative engagement with the ratchet earlier or later in its throw. With this construction the operative throw of the pawl may be varied as desired and the consequent amount of ink supplied correspondingly varied.

The mechanism employed for delivering the ink after it is delivered from the gears may vary widely. These means will, however, preferably include an ink receiving chamber from which it is fed to an ink receiving cylinder. In the construction illustrated in Fig. 2 the ink is delivered from the casing 11 before referred to through a pipe 30 to a chamber 31 formed in a block 31' supported in the frame of the machine. In the construction illustrated, this chamber 31 is a narrow reservoir or conduit adjacent to an ink receiving roll 32 and extends substantially the length of such roll. In the preferred construction, the cross-sectional area of the conduit diminishes slightly from the inlet end, as indicated in dotted lines in the plan view shown in Fig. 1, this construction being adopted so as to provide a constant pressure of the ink throughout the reservoir. The conduit is provided with a discharge throat 33 which, in the particular construction shown, is formed by a pair of plates 34, 35. The plate 34 is a fixed plate and is secured to the wall of the reservoir. The plate 35 is secured to a removable cap piece 36 fastened to the reservoir wall in any suitable manner, as by screw and nut 37. The plate 35 is a flexible plate and is extended beyond the plate 34 so as to lap over onto the ink receiving roll 32. This plate 35 may be adjusted at various points along the periphery of the roll by means of set screws 38, whereby the ink supply to the roll may be somewhat varied at different points.

60 The ink receiving roll 32 delivers its ink to a ductor roll 39 from which the ink is delivered to distributing cylinder 5. The roll 32 and ductor 39 are driven at the same surface speed as the distributing cylinder 5 through any suitable gearing.

The ink receiving roll 32, when employed, is preferably given a reciprocating motion horizontally of the ductor roll 39 to break up the ink and insure a more even distribution. This movement may be given the roll 70 in any suitable manner. In the construction illustrated, the shaft 14 of the distributing cylinder 5 on the other side of the machine is provided with a cam 40 having a cam groove 41 into which takes a stud 42 on an 75 arm 43 pivoted on a stud 44 carried in a bracket 45 suitably secured in the frame of the machine. The other end of the arm 43 carries a stud 46 which takes into a grooved collar 47 on the shaft 48 of the ink receiving roller 32. Through these connections the roll is given a slight reciprocating motion horizontally of the ductor roll.

In some instances it may be desirable to omit the ink receiving roll 32 and the ductor 85 39. In such constructions, the ink is delivered directly from the reservoir to the ink distributing cylinder which, in such cases, becomes an ink receiving cylinder and acts to distribute the ink received by it to the 90 form rollers. Such construction is illustrated in Fig. 4, in which, except for the omission of the ductor and the ink receiving roll, the construction is the same as that heretofore described, the ink being fed to the 95 ink receiving and distributing cylinder under pressure in predetermined quantities at each printing operation of the form cylinder.

While the invention has been shown and 100 described in its preferred form, it will be understood that changes and variations may be made in the various constructions shown and described for carrying it out, and that consequently the invention is not to be limited to the precise construction illustrated.

What I claim is:

1. In an inking mechanism, the combination with a printing couple, of an ink receiving cylinder from which ink is delivered 110 to the form member of the couple, a reservoir from which ink is delivered to the ink receiving cylinder, the cross-sectional area of said reservoir diminishing from the inlet end, and means whereby a predetermined 115 quantity of ink is delivered under pressure to the reservoir at each printing operation of the couple.

2. In an inking mechanism for printing machines, the combination of a printing couple, a pump, means for supplying ink to the pump, means for operating the pump from a moving part of the machine, and connections for delivering ink from the pump to the form carrying member of the 125 couple.

3. In an inking mechanism for printing machines, the combination of a printing couple, a pump, means for supplying ink to the pump, means for varying the deliv- 130

ery stroke of the pump, whereby varying quantities of ink may be delivered, and connections for delivering the ink from the pump to the form carrying member of the 5 couple.

4. In an inking mechanism for printing machines, the combination of a printing couple, a pump, means for supplying ink to the pump, a reservoir to which the ink 10 is delivered from the pump, a delivery orifice from the reservoir, one wall of which is a single flexible plate extending the length of the orifice, and means along the plate whereby the width of the delivery orifice 15 may be increased or decreased to permit varying quantities of ink to be fed through the orifice at different points.
5. In an inking mechanism, the combination with a rotary printing couple, of a 20 distributing cylinder, a pair of gears for measuring ink from a suitable ink supply, and connections operated from the distributing cylinder for actuating the gears to measure out a predetermined amount of 25 ink from the supply at each operation of the distributing cylinder.

6. In an inking mechanism, the combination with a rotary printing couple, of a

distributing cylinder, a pair of gears operating to measure ink from a suitable ink 30 supply, connections operated from the distributing cylinder for actuating the gears to measure out a predetermined amount of ink from the supply at each rotation of the distributing cylinder, and means for varying 35 the operation of the gears while the cylinder is in motion whereby the quantity of ink measured out may be varied.

7. In an inking mechanism, the combination with a rotary printing couple, of a 40 distributing cylinder, a pair of gears operating to measure out ink from an ink supply, connections including a pawl and ratchet operated from the distributing cylinder for actuating the gears to measure out a pre- 45 determined amount of ink at each rotation of the cylinder, and means for varying the throw of the pawl whereby the amount of ink measured by the gears may be varied.

In testimony whereof I have hereunto set 50 my hand, in the presence of two subscribing witnesses.

ELLIS W. COOPER.
